Inventor:

UNITED STATES PATENT OFFICE.

EARL L. ENGLISH, OF CHICAGO, ILLINOIS.

MUTE FOR MUSICAL INSTRUMENTS.

Application filed October 8, 1924. Serial No. 742,355.

My invention relates to a mute for musical instruments, such as the cornet, trombone, trumpet, horn, and the like, and is used to soften and moderate the tones of such instruments; and the main object of the invention is to provide a mute which is strong and durable and will retain its correct shape, and at the same time is light and inexpensive and will also produce a soft and mellow tone.

Several of the mutes on the market are made of papier mâché or of fibre and usually have the larger end closed by a disc or closure of the same material, which is fastened to said end by the use of an adhesive such as shellac. The moisture which usually occurs in the instrument and around the mute, produced chiefly by the saliva and the breath, soon causes the adhesive to soften and thereby permits said end disc or closure to loosen and fall away; furthermore, said moisture also causes both ends of the mute, especially the smaller or tip end, to soften and get out of shape, thereby also injuring or destroying the desired tone effect of said mute. And when such mutes drop out of the instrument and onto the floor, as often occurs, then the ends are frequently injured and broken, and the disc or closure with its adhesive is thereby loosened and falls from the mute. Some mutes are made of metal, like brass, and are thus too heavy in the instrument, while others are made of different metal, but do not produce the desired soft and mellow tones.

It is my special object and purpose to provide a mute which is light and at the same time strong and durable, and also produces a mellow tone, thus to overcome the above noted objections; and this I accomplish by using a light material, such as a fibrous material, for the conical body of the mute, and by reinforcing the ends as with a metal tip and cap, preferably of brass. A further object is to firmly fasten the frictional holding strips on the outside of the mute so that they will not become loose and drop away by reason of moisture in the instrument.

These and other objects and advantageous ends are accomplished with my invention, as will become apparent from the following disclosure taken in connection with the accompanying drawing, in which,

Fig. 1 is a plan view of the preferred form of construction embodying my invention;

Fig. 2 is a longitudinal sectional view thereof, taken on line 2—2 of Fig. 1;

Fig. 3 is a view taken from the smaller end of the mute; and

Fig. 4 is a cross sectional view, taken on line 4—4 of Fig. 2.

The preferred form of construction, as illustrated, comprises a conical body portion or member 8 which is constructed of a light and durable material, preferably a fibrous material, such as papier mâché or fibre or the like. An annular protecting member 9 in the form of a turn-over collar, is clamped on the tip end of said body member 8 and embraces and clamps the inner and outer side of the fibrous material at said end between its two folded walls. This collar is made of thin anti-rust metal, preferably of thin brass, in order to prevent said end of the fibrous material from softening and consequently fraying and becoming out of shape, and this snugly fitting brass collar will also assure a continued, uniform, mellow and subdued tone by the use of this mute.

The larger end of body member 8 is protected and covered by the use of a cap or closing means, which is also made of thin anti-rust metal, preferably thin brass, which closes said end air tight. This cap may consist of a frusto-conical shell or sleeve 10 and a circular end member 11, with an in-turned annular flange 12 thereon, which is clamped air tight over the end rim 10' on member 10, and may further be sealed air tight thereon by the use of solder. These parts 10 and 11 are preferably made in two parts, as shown, for convenience of mounting the sleeve 10 air tight and firmly on member 8, and then mounting the circular member 11 thereon by clamping flange 12 over rim 10', but if preferred parts 10 and 11 may also be made integral.

The cap is preferably fastened over the larger end of the body member 8 by curving an end portion or band 13 of sleeve 10 inward to tightly engage the surface of said member, and furthermore by denting or driving parts of the metal of said band inward to form projections or teeth 14 forced into the fibrous material of member 8, to positively hold said cap on said body member. Fingers 15 are furthermore also fastened on the inside of sleeve 10 with rivets 16, or in any approved manner, and extend inward into the larger end of member 8 to clamp said end between said fingers and the band portion 13. Shellac may also be used

between band 13 and member 8. The cap is thus mounted firmly and air tight over said larger end and provides reinforcing and protecting means for this end of the fibrous body member 8.

Frictional and compressible horn engaging members or holding members 17, of cork, rubber, and the like, are securely and permanently fastened on body member 8, as 10 with one or more rivets 18, which are made level or flush with the inside of said body member and with the outside of said holding members, glue being used in addition to fasten said holding members, thus positively 15 preventing these frictional engaging members 17 from loosening and falling away from member 8, as is frequently the case with the usual mutes having the holding members fastened thereon by the use of adhesive material only, which is loosened by 20 the usual moisture in the horn.

With the above disclosed construction I provide a mute which is light and at the same time strong and durable and can with-

stand falling from the instrument and 25 rough usage, and which with the use of the brass tip and cap also furnishes an especially mellow and subdued tone.

What I claim as my invention and desire to secure by Letters Patent is:

1. A mute comprising a body of fibrous material, and a metal cap fastened over one end of said body to cover said end and having indentations on said cap entering into said fibrous material and inner holding 35 fingers within said cap to securely fix said cap on said body.

2. A mute comprising a frusto-conical body of fibrous material, a cap mounted over the larger end of said body to cover the 40 same and having means engaging into the material of the body, and holding elements provided in said cap for engaging the inner side of said end, to securely fix said cap on said body.

In testimony whereof I have signed my name to this specification.

EARL L. ENGLISH.
